UNITED STATES PATENT OFFICE.

DANIEL A. SCHNABEL, OF ST. PAUL, MINNESOTA.

BOX-FASTENER.

SPECIFICATION forming part of Letters Patent No. 763,430, dated June 28, 1904.

Application filed August 25, 1903. Serial No. 170,672. (No model.)

To all whom it may concern:

Be it known that I, DANIEL A. SCHNABEL, a citizen of the United States, residing at St. Paul, in the county of Ramsey and State of Minnesota, have invented certain new and useful Improvements in Box-Cover Fasteners, of which the following is a specification.

My invention relates to improvements in fastening devices for receptacle - covers, its object being particularly to provide fastening means for covers of such receptacles as bread-holding boxes of such character that the cover will stay connected with the box in open and closed position, but which will allow the cover when in open position to be carried away from the box to permit free access thereto and which will securely lock the cover when in closed position.

To this end my invention consists in the features of construction and combination hereinafter described and claimed.

In the accompanying drawings, forming part of this specification, Figure 1 is a perspective view of a bread-holding box fitted with my improvements. Figs. 2 and 3 are detail views of a portion of one end of the box embodying my improvements, and Fig. 4 is a section on line *xx* of Fig. 2.

In the drawings, A represents a bread-holding box, and B a removable cover therefor.

The cover is secured to the box at each end by a rope or cable 2, secured to the end of the cover and passing loosely through an opening 3 in the adjacent end of the box, the lower end 35 of the rope being formed with a knot 11 to prevent the rope end being drawn through the opening 3. In order to lock each end of the cover in closed position, I provide a clamping device for the rope, consisting of a ring 40 4, through which the rope passes, the ring being formed with a shank 5, passing slidably through a plate 6, set in the end of the box, the end of said shank projecting beyond the outer surface of the box end. Pivoted to the 45 outer end of the shank 5 by a pivot 7 is a locking-lever 8. The pivot 7 is eccentrically positioned in the end 9 of the locking-lever, so that said end serves as a cam when the lever is turned to the position shown in Figs. 2 and 50 4 to grip the rope. In order to prevent accidental turning of the locking-levers, the free

end of each lever is laterally bent, so as to project into a recess 10 in the adjacent end wall of the box when in locking position, as shown in Fig. 2.

As shown in Fig. 1, when the box-cover is secured in closed position the rope will hang outside the ends of the box and be clamped by the locking-levers 7. By turning the locking-levers to the position shown in Fig. 3 the 60 ropes will be released, and the cover may be moved to one side of the box, while at the same time being held connected to the box by the ropes. Loss of the cover is thus prevented.

Having now described my invention, what I claim as new, and desire to secure by Letters Patent, is—

1. The combination with a box and a removable cover therefor, of cables connected 70 with said cover and slidably and non-removably connected with said box, and locking-clamps for said cables carried by said box.

2. The combination with a box and removable cover therefor, of a cable connected with the end of said cover and slidably and non-removably connected with the adjacent end of the box, a clamp engaging with said cable, and means for tightening said clamp upon said cable.

3. The combination with a box and a removable cover therefor, of a cable connected with the end of said cover and slidably through a clamp carried by the adjacent end of the box, and a cam for tightening said clamp upon 85 said cable.

4. The combination with a box and removable cover therefor, of a rope connected with the end of said cover and slidably through the adjacent end of the box, a ring receiving said 90 rope, said ring being formed with a shank slidable through the end of the box, and a locking-lever having an inner cam end pivotally connected with the outer end of said shank, as and for the purpose set forth.

In testimony whereof I affix my signature in presence of two witnesses.

DANIEL A. SCHNABEL.
